The ornamental design for a partitioned wallet and coin purse, as shown and described.

DESCRIPTION

FIG. 1 is a perspective view of a partitioned wallet and coin purse in an open position showing my new design;

FIG. 2 is a rear perspective view thereof, showing the compartment thereon in an open position;

FIG. 3 is a front perspective view thereof in a closed position;

FIG. 4 is a plan view of the interior thereof, in an open position;

FIG. 5 is a plan view of the exterior thereof, in an open position;

FIG. 6 is a front elevational view thereof in a closed position;

FIG. 7 is a rear elevational view thereof in a closed position; and,

FIG. 8 is a side elevational view thereof in a closed position.

FIG. 1

FIG. 3
